UNITED STATES PATENT OFFICE.

WARREN B. BUCKLEY, OF NEW YORK, N. Y.

DESIGN FOR A TIRE-TREAD.

50,828.

Specification for Design.

Patented May 29, 1917.

Application filed March 28, 1917. Serial No. 158,132. Term of patent 14 years.

To all whom it may concern:

Be it known that I, WARREN B. BUCKLEY, a citizen of the United States, residing at No. 151 West Seventy-sixth street, New York, in the county of New York and State of New York, have invented a new, original, and ornamental Design for a Tire-Tread, of which the following is a specification, reference being had to the accom-

panying drawing, forming a part thereof, in which—

Figure 1 is a perspective view, and
Fig. 2 is a plan view of a portion of a
tire tread, showing my new design.

I claim:

The ornamental design for a tire tread,
as shown.

WARREN B. BUCKLEY.
